UNITED STATES PATENT OFFICE.

JOHN T. ROBERTS, OF WASHINGTON, DISTRICT OF COLUMBIA.

WARMER.

1,105,307.

Specification of Letters Patent. Patented July 28, 1914.

Application filed December 1, 1913. Serial No. 803,964.

To all whom it may concern:

Be it known that I, JOHN T. ROBERTS, a citizen of the United States, residing at Washington, in the District of Columbia, have invented certain new and useful Improvements in Warmers, of which the following is a specification.

The present invention relates to improvements in warmers; and it consists in the construction, combination and arrangement of parts hereinafter set forth and pointed out in the claims.

The accompanying drawing illustrates a simple and approved reduction of the improvement to practice, and in the said drawing: Figure 1 is a perspective view of a foot warmer constructed in accordance with the present invention, Fig. 2 is a central vertical longitudinal sectional view of the same, Fig. 3 is a transverse section on the line 3—3 of Fig. 2, Figs. 4 and 5 are similar sectional views but illustrating different forms of construction, Figs. 6, 7, 8 and 9 illustrate warmers embodying the principle of my invention and adapted to be applied to various portions of the human body for the alleviation of pain through the process of heat.

The improvement may be constructed in any desired shape, and in any proportion best suited for the purpose for which the device is intended.

In Figs. 1 to 5 of the accompanying drawings, I have illustrated simple and approved types of the invention which are in the nature of foot warmers, each of which including an outer casing 1 which is preferably formed from a single sheet of comparatively thin metal, such as sheet iron and which is provided with a bail or handle; the handle, shown in Fig. 1, being substantially U-shaped, and indicated by the numeral 2, while the handle, 2', in Fig. 2 of the drawing is ring-shaped, having split ends which may be inserted through the metal casing 1 or which may be secured to the casing through the medium of a bent strip passing through a suitable opening in the casing and which has its ends bent in opposite directions from the said opening. In all of these figures I have illustrated a rounded core 3, in the nature of a heat-carrying element or radiator, and preferably formed of a single cube of porous metal, such as cast iron. Tamped within the casing 1 and entirely inclosing the radiator core 3 is a filler of heat-distributing material 4. This mate-

rial may comprise powdered soapstone, brick dust, sand and a proper proportion of cement to which is added a sufficient quantity of water to render the same plastic, but which after being tamped around the core 3 is allowed to set and harden. The material in its hardened state is practically non-breakable, but at the same time diffuses or distributes heat from the radiator 3 at such a degree that the device will retain its warmth for a great length of time.

After the material comprising the heat distributer 4 becomes hardened around the core 3, these two elements become joined and inseparable, and the said material being tamped into the casing 1 will, when set, join or connect itself with the said casing, so the casing, the heat distributer and the core, while each formed of different material, are so associated as to provide a single member made up of inseparable elements. All of the said elements are co-extensive one with the other. This particular and peculiar construction and arrangement is essential in attaining the primary object for which this invention is designed; that is, to produce a warmer which will diffuse the heat evenly, at a higher temperature, and for a greater period of time than is possible with warmers, of the ordinary construction, wherein the core or radiator is removed for heating and replaced within a casing for diffusing the heat. With my construction the casing first receives the units of heat which pass therefrom through the distributing substance 4 to the radiator or core 3. The core, being of porous metal, quickly absorbs the heat, and would also quickly diffuse the same (after the warmer is heated) were the heat units not halted temporarily by the plastic distributer 4 and the thin metal casing 1. Thus the casing 1 and the distributer 4 restricts the outflow of heat, so that the units of heat are diffused slowly but at almost a uniform temperature for the length of time the warmer remains heated, such length of time being, as stated, greatly in excess of any similar warmer which has come under my observation.

The device is heated by placing the same in an ordinary hot oven, the heating chamber of a sterilizing apparatus, or over a burner, or by immersing in a vessel of boiling water and may then be inclosed or wrapped within a cloth, as indicated by the dotted lines in Fig. 3, and designated by

the numeral 5 in the said figure. The device may be used under bed clothing or may be carried in the pocket of the owner, and, of course, the device may be applied to the different parts of a person in lieu of the usual hot water bag. The devices illustrated in the remaining figures of the drawing are provided for relieving or alleviating pain from the human body and which are adapted 10 to be employed in lieu of the ordinary hot water bottle or similar easily constructed devices. In Fig. 6 there is shown two members each of a similar construction which have their edges almost meeting to provide 15 what may be termed a cradle which serves as a rest for arms or shoulders. Each of these members, indicated by the letter A includes a casing which comprises a flat bottom, a vertical end, a downwardly curved top and 20 vertical sides. Each of the members is provided with a handle 2^a, and the interior construction of the said members is substantially similar to that heretofore described, a radiating core 3 being arranged longitudinally 25 of each of the members and the said core is entirely surrounded with a heat distributing filler 4. Each member A may be used separately when desired and may be placed against the side, thigh or shoulder of a patient to draw pain from the diseased parts. 30 The member A can be turned upside down to adapt itself to the shoulder or spinal column of the patient, while it can also be turned upon one of its sides and applied to 35 the shoulder and back of the patient.

In Fig. 7 two substantially wedge-shaped members B—B are illustrated, each of which comprising an outer casing having a longitudinally arranged radiating core 3 and a 40 filler of heat-distributing material 4, which surrounds the core and which fills the casing. Each of the members B is provided with a stationary handle 2^b. These members may be used separately and applied to a patient's 45 shoulder or back, or may form a cradle, as illustrated for the reception of the legs or arms of the patient to draw the pain from these parts.

In Fig. 8 I have illustrated the device 50 designed especially for the alleviation of pains in the small of the back. In this figure the casing C has a curved top, a flat bottom and vertical sides connecting the bottom with the top. The core is shown by the dotted lines, and is indicated by the numeral 3, while the sides have secured thereto handles 2^c.

In Fig. 9 the device is illustrated constructed especially for the alleviation of 60 pains in the legs or arms of a patient. The casing D includes a flat bottom and right angular ends and sides. The top is curved inwardly from its connection with the ends of the casing, and the said ends are provided with handles 2^d. Also in Fig. 9 I

have illustrated a pan or tray which is indicated by the character E, the said pan or tray supporting the casing D. The tray E comprises a rectangular member which is of a size to receive any of the structures above set forth and includes a false bottom e', a bottom e'' spaced a suitable distance from the false bottom e', while between the bottom plates e' and e'' is arranged a plurality of sheets of non-heat conducting material, indicated by the character f. The sides and ends which connect the bottom plates e' and e'' are indicated by the character e, and project a suitable distance above the false bottom e'. The tray E is designed 70 to receive a warmer to prevent the same burning the mattress or bed clothing of the bed in which the patient is arranged. The structure as illustrated in Fig. 9 embodies 75 the principle of the structures heretofore described, but, if desired, two cores or radiating members 3 may be employed, the same members being indicated by the dotted lines 80 in the said figure.

From the above description, taken in connection with the accompanying drawings, the simplicity of the device, as well as the advantages thereof will, it is thought, be perfectly apparent to those skilled in the art to which such inventions appertain 90 without further detailed description. It may be stated, however, that the ends of the casings illustrated in Figs. 1 to 5 may be closed, or the said ends may be slightly bent 95 inwardly, as shown in Fig. 2 of the drawings, and indicated by the character x, and further that the device is not adapted to be received within any outer casing, a cloth, either damp or dry, applied to the casing of any of the structures having, from actual 100 tests, proved sufficient to prevent the warmer from burning or blistering the part to which it is applied.

Having thus described the invention, what I claim is:

1. In a device for the purpose set forth, a casing, a plastic heat distributor filling the casing, and a radiating core embedded within and entirely surrounded by the plastic material.
2. In a device for the purpose set forth, a sheet metal casing, a filler of plastic heat-distributing material within and filling the casing, and a heat radiating core centrally embedded within the plastic material and co-extensive with the casing.
3. In a device of the class set forth, a casing of thin material, a plastic body of heat distributing material filling and adhesively connected with the casing, and a core of porous material embedded within the plastic material and co-extensive therewith.
4. In a warming device, a casing, a plastic body of heat distributing material tamped within the casing, and a porous core embed- 130

ded within the heat distributer and extending centrally and longitudinally thereof.

5. In a warming device of the class set forth, a plastic body of heat distributing material, a core embedded within the heat distributer, and a casing co-extensive with and entirely inclosing the plastic distributer.

6. In a device for the purpose set forth, a casing, a plastic heat distributer filling the 10 casing, a radiating core embedded within

and entirely surrounded by the plastic material, and the casing, heat distributer and core being inseparably connected.

In testimony whereof I affix my signature in presence of two witnesses.

JOHN T. ROBERTS.
